UNITED STATES PATENT OFFICE.

WILLIAM HENRY WADSWORTH, OF BROOKLYN, NEW YORK, ASSIGNEE TO WILLIAM H. WADSWORTH AND DAVID R. WADSWORTH, JR., BOTH OF BROOKLYN, NEW YORK.

RADIATOR-CAP.

1,263,490.

Specification of Letters Patent. Patented Apr. 23, 1918.

Application filed March 16, 1917. Serial No. 155,156.

To all whom it may concern:

Be it known that I, WILLIAM HENRY WADSWORTH, a citizen of the United States, and resident of the borough of Brooklyn, 5 county of Kings, city and State of New York, have invented certain new and useful Improvements in Radiator-Caps, of which the following is a specification.

By the term radiator I refer more particularly to the radiators of automobiles and so that my device may be fully understood and appreciated I will first describe the ordinary and well-known construction.

Each radiator is fitted with a screw 15 threaded nozzle through which water is introduced into the radiator and upon the screw threads of the nozzle a cap is placed which must be entirely removed when the radiator is to be filled.

Owing to the expansion and contraction 20 it is sometimes quite difficult to remove the radiator cap and particularly if the cap has been screwed down tight when the radiator is cold and therefore many automobile 25 drivers allow the cap to remain partially insecure with the result that radiator caps are oftentimes lost or, because they must be entirely removed, they are very often mislaid.

To overcome the inconveniences due to the 30 misplacement or loss of a radiator cap I have devised the construction which I will now describe, which has for its purpose a cap or closure for radiators that will always 35 remain in position and will automatically retain a closed position when not deliberately secured open.

The following is what I consider a good 40 means of carrying out my invention and the accompanying drawing should be referred to for a complete understanding of the specification which follows.

In the drawing:—

Figure 1 shows a partial sectional view of 45 my device.

Fig. 2 an elevation thereof.

Fig. 3 a plan view.

Fig. 4 a plan view of a part removed.

Similar reference numerals indicate like 50 parts in all of the figures where they appear.

As in the use of my device it is not necessary to modify or change the construction of the radiator I have not shown a complete 55 radiator but only the upper portion thereof.

In the drawing the radiator as a whole is indicated at 1.

Secured to the radiator and communicating with a perforation therein is an outwardly extending screw threaded nipple 2. 60 Upon the nipple 2, which may be of any length, I arrange a cylindrical member 3, having screw threads 4, by which it is attached to the nipple 2. The upper end of the cylindrical member 3 may have a filling 65 nozzle or funnel 5, of any desired shape, but in the drawing I show merely a semi-circumferential lip arranged at one side of the member 3. Within the lip is a flange 6, formed integral with the member 3 or secured thereto, and at the side of the flange opposite the highest part of the lip 3 I provide bearings 7, for a shaft 8, and formed integral with the bearings is an upwardly or outwardly extending resilient member 9, 70 which may be termed a post. Upon the post 9, I arrange a hook 10 for a purpose that shall appear later.

Rotatable upon the shaft 8, is a disk 11, having an upwardly or outwardly projecting portion 12. The portion 12 passes through the center perforation of the flange 6, and the disk 11, projecting beyond the portion 12, finds a bearing upon the inner side of the ring 6. 85

Formed integral with the disk 11 or secured therein is an operating handle or lever 13, projecting beyond the side of the member 3.

Upon the shaft 8, I arrange a spring 14 90 as shown in Fig. 4, and the center elongated loop 15, of the spring, bears upon the under side of the member 11, at a point beyond the center thereof. The spring 14—15 urges the disk 11 upward and outward so that 95 under normal conditions and under the influence of the spring the disk 11 will bear firmly and reliably upon the flange 6.

To secure my device upon the screw threads of the nipple 2, I provide a set 100 screw 16, but as it will probably not be necessary to remove my device it will be understood that it may be secured to the nipple 2 by soldering or brazing, or the cylindrical member 3 may be permanently secured to 105 the radiator without the use of the nipple 2.

From the description of my device it will be seen that the passage into the radiator is normally closed. When it is desired to introduce water into the radiator, the lever 110

13 is lifted, this will force inward and downward the disk 11 and part 12, compressing the spring 15 or partially rotating it in a manner well understood with springs 5 of this character. The lever 13 is then engaged upon the hook 10, and water may be introduced into the radiator by being poured over the lip 5.

When the radiator is filled to the proper 10 point the lever 13 is disengaged and the spring will automatically return the disk 11 and projection 12 into the position shown, thus closing the passage of the radiator.

Parts may be used without the whole, the 15 loop 5 may be omitted, the projecting portion 12 may be omitted or may be substituted for by a decorative member, other modifications as to shape and size may be made within the scope of the appended 20 claims without departing from the principle or sacrificing the advantages of the invention.

I see no reason why the whole device could not be made on a cone or funnel shape, the 25 upper portion being larger than the lower may materially assist in the introduction of water into the radiator.

Having carefully and fully described my 30 invention what I claim and desire to secure by Letters Patent is:

1. A device of the character described

comprising a cylindrical member having screw threads at one end and an inwardly projecting flange at the other end, means 35 interior of said cylindrical member for closing the passage through said flange, a double coiled spring for urging said closing means into a closed position, means for opening said closing means and means formed integral with said flange and coöperating 40 with said closing means for retaining said closing means in an open position.

2. A device of the character described comprising a cylindrical member, an inwardly projecting flange formed integral 45 therewith, a plurality of bearings in said flange, a shaft through said bearings, a disk rotatable on said shaft, a spring having a plurality of coils upon said shaft for rotating said disk upon said flange, a lever 50 formed integral with said disk for rotating said disk and means secured to said flange coöperating with said lever for retaining said disk in an open position.

Signed at New York city, county and 55 State of New York this 10 day of March, 1917.

WILLIAM HENRY WADSWORTH.
